DESIGN FOR AN EARRING OR SIMILAR ARTICLE

John Montaquila and Samuel Montaquila,
Cranston, R. I.

Application September 12, 1946, Serial No. 133,266

Term of patent 3½ years

(Cl. D45—9)

To all whom it may concern:

Be it known that we, John Montaquila and Samuel Montaquila, citizens of the United States of America, residing at Cranston, in the county of Providence and State of Rhode Island, have invented a new, original and ornamental Design for an Earring or Similar Article, of which the following is a specification, reference being had to the accompanying drawing, forming part thereof.

We claim:

The ornamental design for an earring or similar article, substantially as shown.

JOHN MONTAQUILA.
SAMUEL MONTAQUILA.
